UNITED STATES PATENT OFFICE.

WALTER W. BROWN, OF ERIE, PENNSYLVANIA.

COMPRESSOR.

1,142,299.

Specification of Letters Patent. Patented June 8, 1915.

Application filed March 12, 1914. Serial No. 824,149.

To all whom it may concern:

Be it known that I, WALTER W. BROWN, a citizen of the United States, residing at Erie, in the county of Erie and State of Pennsylvania, have invented new and useful Improvements in Compressors, of which the following is a specification.

This invention relates to compressors and consists in certain improvements in the construction thereof as will be hereinafter fully described and pointed out in the specification and claims.

More particularly the invention relates to the inlet and discharge valve mechanism of a compressor. Some difficulty has been encountered with compressors in the heating of the discharge valve by discharged air or gases.

One of the objects of the invention is to reduce this by drawing the air into the compressor in passages adjacent to the discharge passages. In carrying out the invention the inlet valve is arranged within the discharge passages so that the incoming air cools the valve.

The invention is illustrated in the accompanying drawings as follows:

Figure 1 is a central section through a compressor. Fig. 2 a side elevation of one of the valve disks. Fig. 3 a plan view of the same. Fig. 4 a section on the valve member. Fig. 5 a plan view of the same part. Fig. 6 a section of a spring supporting cap. Fig. 7 a plan view of the same part. Fig. 8 an enlarged view, partly in section and partly in elevation of the valves.

As shown the compressor is formed for two stage compression.

1 marks the low pressure cylinder, 2 the high pressure cylinder, 3 the low pressure piston, 4 the high pressure piston and 5 the intercooler. These parts may be of any desired construction, the one shown being adapted to be used with a Diesel engine.

In order to regulate the amount of air drawn into the cylinder, I provide a valve mechanism made up of a cylindrical shell 6 having a series of longitudinal slots 8. This shell is extended over a somewhat similar shell 7 and is telescopically mounted on the shell 7, the shell 7 having the longitudinal slots 9 for the admission of air. The shell 7 has the head 10 with the openings 11

through it. A screw 12 is secured to the head 10 and extends through a head 13 on the shell 6. By simply turning the shell 6 it may be adjusted up or down on the shell 7 thus opening or closing a portion of the slots 8 and 9, thus increasing or decreasing the capacity of the inlet. The shell 6 is locked in adjustment by a lock nut 14 and it has its outer surface knurled at 15 so that it may be more readily turned.

The shell 7 is screwed into an inlet member 16. A valve member 17 is secured to the inlet member and the spring supporting member 18 is secured to the valve member. A bolt 19 is screwed into the spring supporting member 18 and extends upwardly through the valve member and through a head 22 in the inlet member 16. A nut 23 is arranged on the bolt 19 by means of which the three members, the inlet member 16, the valve member 17 and the spring supporting member 18 are securely clamped together so that the valve mechanisms form a construction as a unit which may be attached as a unit to the compressor. The joint 20 between the inlet member and valve member is formed by the inlet member telescoping slightly the valve member, the inlet member seating on a shoulder on the valve member. The head 22 has the passages 24 through it so that the air entering through the slots 8 and 9 may pass through the shell 7 and through the head 24 through the inlet member into the valve member. The valve member has a series of passages 25 extending in an axial direction from the central passage 25 of the valve member and these passages 25 extend through the seat 26 on the bottom of the valve member. A valve disk 27 is adapted to close the passage 25 by seating on the seat 26. A spring 28 tends to hold the valve 27 to its seat, the spring being arranged in a socket 29 in the spring supporting member 18. On the in stroke of the compressor the air passes by way of the passage 25 through the passages 25, valve 27 and through the valve pocket 30 and inlet passage 31 to the compressor.

The air is discharged to the passage 32 extending from the pocket, the passage 32 connecting with an annular passage 33 in the pocket formed around the valve member and inlet member. The valve pocket has the

shoulder 34 and the inlet member has the shoulder 35 adapted to seat on the shoulder 34, a packing 36 being preferably used on the seat. The pocket also has the shoulder 37 on which the shoulder 38 of the valve member seats, a gasket 39 being preferably used on this seat. The space between the valve member and the pocket below the gasket 39 forms a passage 40 through which the air is discharged, the air entering the passages 41 in the valve member. The passages 41 extend through the seat 42 on the top of the valve member and the valve disk 43 exactly similar to the valve disk 26 is adapted to close the passage by the valve member operating on the seat. The valve 43 is carried to its seat by gravity. Its upward movement is limited by the shoulders 44 arranged on the periphery of the inlet member 16.

The operation of the device is as follows:—Air is drawn in through the slots 7 and 8, passing down through the inlet member by way of the passages 24 through the valve member by the passages 25 through the passages 25, the difference in pressure opening the valve 27. The air is discharged to the pocket 30 and passes by the passage 31 to the compressor. On the discharge stroke the air passes by way of the discharge 40 surrounding the valve member to the passages 41, thence by way of the valve to the discharge passages 33 and 32. It will be observed that the discharge passages surround the inlet passages and the discharge valve is in contact with the walls inclosing the inlet passage. As the normal temperature air is drawn through the inlet passages it cools the walls of these passages thus reducing the temperature of the parts subjected to the heat of the discharged gases.

By taking the air into the compressor and discharging it through the same passage a discharge of lubricant is largely avoided because the velocity of the incoming air and the time during which it is delivered has a greater driving force than the air being discharged. As a consequence the tendency is to drive any lubricant which may reach the port leading to the cylinder back into the cylinder.

What I claim as new is:

1. In a compressor, the combination of a cylinder; a piston in said cylinder; inlet and discharge valves for said cylinder comprising an inlet member; a valve member secured to said inlet member having concentric passages in the valve member in opposite directions; and concentric check valves seating on said valve member in opposite directions and controlling said passages.

2. In a compressor, the combination of a cylinder; having a valve pocket, said pocket having a discharge opening and an opening

leading to the cylinder, the pocket having annular shoulders at opposite sides of the discharge passage; an inlet member seated on one of said shoulders; a valve member seated on the other of said shoulders and forming a joint with the inlet member, said valve member having oppositely directed passages; and a valve disk controlling the discharge passages arranged between the inlet member and the valve member, the valve disk controlling the inlet passages.

3. In a compressor, the combination of a cylinder having a valve pocket, said pocket having a discharge opening and an opening leading to the cylinder, the pocket having annular shoulders at opposite sides of the discharge passage; an inlet member seated on one of said shoulders; a valve member forming a joint with the inlet member and seating on the other of said shoulders, said valve member having passages leading in opposite directions, one leading from the inlet and the other to the discharge; a spring cap arranged on the valve member; a bolt for clamping the inlet member, valve member and spring cap together; and valves seating on the passages in the valve member.

4. In a compressor, the combination of a cylinder; a piston therein; inlet and discharge valves connected with the cylinder comprising an inlet member having a webbed head therein; a valve member forming a joint with the inlet member, said valve member having passages extending in opposite directions, one from within the valve member and the other from without the valve member; seats at the ends of the valve member surrounding said passages; and valves operating on said seats.

5. In a compressor, the combination of a cylinder; a piston therein; inlet and discharge valves connected with the cylinder comprising an inlet member having a webbed head therein; a valve member forming a joint with the inlet member, said valve member having passages extending in opposite directions, one from within the valve member and the other from without the valve member; seats at the ends of the valve member surrounding said passages; valves operating on said seats; and means for clamping the inlet and valve members together.

6. In a compressor, the combination of a cylinder; a piston therein; an inlet valve for the cylinder; a regulator for the inlet valve comprising telescoping shells each having slots; a screw extending from one of said shells through the opposite shell; and means for adjusting one of said shells on said screw to vary the opening to the inlet.

7. In a compressor, the combination of a cylinder; a piston therein; an inlet valve for the cylinder; a regulator for the inlet valve

comprising telescoping shells, each of said shells having slots and a head; and a screw secured to the head of one of said shells and having a screw threaded connection with the other of said shells, said shells having slots therein adapted to be varied by the telescoping of one shell upon the other.

In testimony whereof I have hereunto set my hand in the presence of two subscribing witnesses.
